UNITED STATES PATENT OFFICE

WALTER T. ROLFE, OF AUSTIN, TEXAS, ASSIGNOR TO INTERNATIONAL SILVER COMPANY, OF MERIDEN, CONNECTICUT, A CORPORATION OF NEW JERSEY

DESIGN FOR A SPOON OR SIMILAR ARTICLE

Application filed March 28, 1929. Serial No. 30,646. Term of patent 7 years.

To all whom it may concern:

Be it known that I, WALTER T. ROLFE, a citizen of the United States, residing at Austin, county of Travis, State of Texas, have invented a new, original, and ornamental Design for a Spoon or Similar Article, of which the following is a specification, reference being had to the accompanying drawing, forming part thereof.

Fig. 1 is a front view of a spoon showing my new design.

Fig. 2 is a section on line 2—2 of Fig. 1.

Fig. 3 is a section on line 3—3 of Fig. 1.

The back is a plain or other conventional design.

I claim:

The ornamental design for a spoon or similar article substantially as shown and described.

WALTER T. ROLFE.
